UNITED STATES PATENT OFFICE.

THOMAS GOODREM AND CHAS. JACKSON, OF PROVIDENCE, RHODE ISLAND.

IMPROVEMENT IN ROTATING PROJECTILES FROM SMOOTH-BORED ORDNANCE.

Specification forming part of Letters Patent No. 36,001, dated July 29, 1862.

To all whom it may concern:

Be it known that we, THOMAS GOODREM and CHARLES JACKSON, both of Providence, in the county of Providence and State of Rhode Island, have invented certain new and useful Improvements in Elongated Projectiles for Ordnance; and we do hereby declare that the following is a full, clear, and exact description of the same, reference being had to the accompanying drawings, making a part of this specification, in which—

Figure 1 is an outside longitudinal view of an elongated projectile with our improvements. Fig. 2 is a central longitudinal section of the same. Fig. 3 is a transverse section of the same. Fig. 4 is an outside view of one of the friction-rollers and its supporting-lever.

Similar letters of reference indicate corresponding parts in the several figures.

This invention has for its object the obtaining of a rotary motion of an elongated projectile on its axis in its discharge from a smooth-bore gun; and to this end it consists, principally, in fitting such a projectile with friction-rollers so arranged to protrude through slots in the sides of the projectile from a cavity in the interior thereof that their peripheries may roll in contact with the bore of the gun when the projectile is placed therein, and that their planes of rotation will be oblique to the axis of the said bore and of the projectile, such rollers having springs or their equivalents applied, in combination with their bearings in the cavity of the projectile, for the purpose of holding them with a sufficient but not too unyielding pressure against the bore, that in rolling in contact therewith they may, owing to the aforesaid obliquity of their planes of rotation, run in a spiral direction, and so cause the projectile to receive a rotary motion on its axis in its discharge.

To enable others skilled in the art to make and use our invention, we will proceed to describe its construction and operation.

A is the body of the projectile having an external circumference nearly large enough to fit the bore of the gun in which it is to be used, and having a deep cavity, *a*, in its rear for the reception of the levers B B B, which constitute or contain the bearings for the friction-rollers C C C and of the follower D, by which the said levers are held or forced out to a position to cause the friction-rollers to protrude

in a suitable manner through the exterior of the body A. The said levers B B B are fitted and partly received within grooves *b b b*, provided in the cavity *a*, and each of said levers is furnished near its rear end with a tenon, *c*, which enters a mortise, *d*, in the back of the said groove, to prevent its longitudinal displacement. The bearings for the journals *e e* of the friction-rollers are near the front ends of their respective levers, consisting simply of recesses in the edges of the lever on opposite sides of mortises *g g g*, which are provided in them for the reception of the friction-rollers. The slots *fff*, provided in the sides of the body A to permit the protrusion of the friction-rollers, are oblique to the axis of the projectile to correspond with the obliquity of the rollers.

To facilitate the construction of the projectile, the grooves *b b b*, for the reception of the levers B B B, are made parallel with the axis of the projectile, and the obliquity of the rollers to the said axis is produced by arranging the mortises *g g* and the bearings for the journals *e e* in oblique positions. The angle of the obliquity to the axis is made less or more acute, according as a greater or less rotary movement of the projectile is desired. The follower D is made of such form that a portion of it enters the cavity *a a* in the body A, and this portion is made with as many flat sides as there are friction-rollers, (three represented in the drawings,) and in a dovetail mortise in each of said sides there is inserted a piece of india-rubber, *h*, to constitute a spring or elastic bed for the support of one of the levers, to hold or press it outward with a yielding pressure for the purpose of pressing out its respective roller against the bore of the gun. The said flat sides of the follower may be so arranged as to act upon the levers like wedges, to force them outward by the driving of the follower into the projectile. The body A, the levers, the rollers, and the follower may all be of cast-iron and cast to go together without any fitting. The levers and rollers may be "malleableized" by the process commonly adopted in making malleable iron.

Before loading the gun the follower D is not driven far enough into the body A and between the levers B B to make the rollers protrude very far from the slots *ff*, in order that in loading too much difficulty may not arise

from the friction of the rollers; but in ramming the ball home the follower is caused to enter further into the body, and the rollers are thereby driven out or pressed harder against the sides of the gun, and this pressure will be further increased in the act of discharging by the pressure of the gases against the follower unless the head of the follower has been previously brought up against the base of the body A. The pressure thus produced insures a sufficient friction between the peripheries of the rollers and the surface of the bore of the gun to insure the rotation of the rollers upon their axes as the projectile is driven through, and this rotation, being in a direction oblique to the axis of the bore and projectile, causes the rollers to travel along the bore in a corresponding oblique direction, by which means they are caused to describe spiral lines within the bore, and to impart to the projectile a movement about its axis which is continued throughout its flight.

That the projectile may not be detached from the follower during its flight, or before it is placed in the gun, a set-screw is inserted at the point L in the cylindrical portion of the former, midway between two of the levers, the end of which, when screwed up, will enter one of three mortises made in the three straight sides of the follower opposite each other. The mortises are of sufficient length to allow the head of the follower to be brought up to the base of the projectile without hinderance from the screw.

The expanding packing represented in Figs. 1 and 2 is composed of two rings or bands, F and G, of brass, copper, or other not too hard or too soft metal or alloy, and one or more interposed rings or bands, H, of canvas or other woven or fibrous substance saturated with grease. The metal bands are of slightly conical form, smaller in front, and the interposed band assumes a similar form. The outer metal band, F, is attached to the rear end of the body A of the projectile by means of a portion of the rear of the exterior being of conical form, largest at the base, and fitting into the said band, as shown at i i in Fig. 2.

In order to get the front part of the band over the portion i i of the body, it is made of a strip of sheet metal, and its ends are not secured together until it has been lapped round

the portion i i, when its ends are riveted together, as shown at j j in Fig. 1. The said ring or band is slit in several places, as shown at k k, to enable it to be expanded easily in a circumferential direction. The inner metal band, G, is made in a similar way to F; but its ends should not be secured together. The interposed band or bands are made of strips of canvas, cloth, or felt slit at intervals in a similar manner and for a similar purpose to the metal bands. The band F is the only one which comes upon the body A of the projectile. Those G and H are contained within the portion of F which projects beyond the rear of the body. The portion of the follower D which does not enter the body is made conical, and of a size to enter the inner ring, G, as shown in Fig. 2. The expansion of the packing against the bore of the gun is produced by driving the body toward the follower, or vice versa, either by the act of ramming the projectile into the gun or by the act of discharging it. This kind of packing is very flexible, adapts itself readily to the exact form of the bore to prevent windage around the exterior of the projectile, and, when applied in combination with the follower D to the kind of projectile described, it also prevents windage through the cavity a and slots f f, and steadies the projectile in its movement on and with the rollers.

We do not claim the fitting of a projectile with anti-friction rollers to reduce its friction in the bore in loading and discharging; but

What we claim as our invention, and desire to secure by Letters Patent, is—

- Having the rollers arranged to rotate obliquely in respect to the axis of the projectile, substantially as herein shown and described, so that the projectile as it moves through the gun will be caused to rotate, all as set forth.
- The combination of the rollers C with the levers B and follower D, substantially as herein shown and described.
- The elastic beds h, in combination with the rollers C and follower D, as herein shown, and described.

THOMAS GOODRÉM,
CHARLES JACKSON.
